UNITED STATES PATENT OFFICE.

BRUNO STECHBART, OF CHICAGO, ILLINOIS, ASSIGNOR, BY MESNE ASSIGNMENTS, TO
AMERICAN PROJECTING COMPANY, OF CHICAGO, ILLINOIS, A CORPORATION OF
DELAWARE.

MOTION-PICTURE MACHINE.

1,287,499.

Specification of Letters Patent. Patented Dec. 10, 1918.

Original application filed May 7, 1917, Serial No. 166,865. Divided and this application filed February 5, 1918. Serial No. 215,447.

To all whom it may concern:

Be it known that I, BRUNO STECHBART, a citizen of the United States of America, and a resident of Chicago, in the county of Cook, State of Illinois, have invented certain new and useful Improvements in Motion-Picture Machines, of which the following is a specification.

This invention relates to the type of portable motion picture machines described in detail in my prior application for Letters Patent, Serial No. 166,865, filed May 7, 1917, whereof the present application is a division.

The object of the present improvement is to provide a simple and efficient means for effecting a tilting adjustment of the machine, as a whole, in a vertical plane in attaining a proper positioning of the pictures on the exhibition or view screen, all as will hereinafter more fully appear.

In the accompanying drawings:

Figure 1, is a perspective view of a portable motion picture machine of the rectangular box form, and having the present improvement applied.

Fig. 2, is an elevation of the side of the machine opposite to that shown in Fig. 1.

Fig. 3, is an enlarged detail vertical section, illustrating the adjusting means of the present improvement.

Like reference numerals indicate like parts in the several views.

Referring to the drawing, 1 designates a box or casing, preferably of the rectangular form shown, and adapted to inclose the film feeding, film guiding and film reeling mechanisms of a motion picture machine, and afford support for the usual projection objective 2, lamp house 3 and condenser usually associated with the aforesaid mechanisms. In construction shown the main portions of the side walls of the casing are hinged to the other portion of the casing to constitute entry doors 4 and 5 to the inclosed mechanisms and parts.

6 designates a removable crank or handle for operating the film feeding mechanism, and 7 designates a removable crank or handle for operating the film rewinding mech-

anism of the machine, as described in detail in my aforesaid application Serial No. 166,865.

8 designates a pair of adjustable legs, preferably formed with semi-spherical enlargements 9 at their lower ends, and having movement in a plane at right-angles to the optical axis and light passage of the machine. The legs 8 have engagement in guide orifices in the bottom web of the casing 1, and in guide bushings 10 in the front web of said casing, as shown.

11 designate clamping screws associated with the bushings 10 and adapted to clamp the legs 8 at their required adjustments.

12 designates companion semi-spherical buttons attached to the aforesaid bottom web of the casing 1 near the rear corners of the same, and adapted to act as rockers for the casing 1 in the tilting adjustments of the same, which in the present structure is attained by the adjustment of the legs 8 aforesaid to properly tilt the casing 1 and objective 2, so that the pictures projected will be displayed in proper position on the view or exhibition screen.

Having thus fully described my said invention what I claim as new and desire to secure by Letters Patent, is:

1. In a motion picture machine, the combination of a casing, an objective arranged horizontally near the upper and front end of the same, a leg slidably arranged at the lower and front end of the casing in right angle relation to the axis of the objective, and means for securing said leg at the required adjustment, substantially as set forth.

2. In a motion picture machine, the combination of a casing, an objective arranged horizontally near the upper and front end of the same, a leg slidably arranged at the lower and front end of the casing in right-angle relation to the axis of the objective, means for securing said leg at the required adjustment, and a supporting button attached to the lower and rear end of the casing, substantially as set forth.

Signed at Chicago, Illinois, this 1st day of February, 1918.

BRUNO STECHBART.
